HEMP TURNING MACHINE

Joseph B. Kucera, Traer, Iowa

Application January 7, 1944, Serial No. 517,453

5 Claims. (Cl. 56—370)

This invention relates generally to machines for turning over windrowed hemp and the like and in particular to a hemp turning machine capable of uniformly picking up the hemp, moving the hemp in a smooth unbroken stream through the machine, and then discharging the hemp in a turned over position relative to its position when picked up. This application is a continuation-in-part of application Serial No. 472,975, filed January 20, 1943.

Hemp is generally cut in windrows and positioned transversely of a windrow with the butt ends at one side of a windrow. One side of the hemp is first retted or seasoned and the hemp is then turned over to season the other side. Since hemp often grows to lengths of twelve and fifteen feet many difficulties have been encountered in uniformly feeding the hemp into the pick-up means of the hemp turning machine and in carrying the hemp on the pick-up means and through the machine in a smooth unbroken flow. The pick-up means is generally comprised of a series of downwardly and forwardly extended arms, each of which is provided with an endless conveyor movable along the top and bottom of an arm and having pick-up fingers in a spaced relation. Due to the length of the hemp it is impractical to construct a pick-up means having a width in the neighborhood of from twelve feet to fifteen feet because of the resultant large size and expense of the pick-up means as well as the inconvenience in handling and storing the over-all hemp turning machine.

Where the width of the pick-up means is appreciably less than the length of the hemp, it is apparent that the portion of the hemp not supported on the pick-up means will tend to tip downwardly. As a result the hemp becomes tangled as it progresses into the machine. A further difficulty in picking up hemp arises from its cane-like structure which causes the hemp to roll ahead of the pick-up arms and accumulate in bunches forwardly of the pick-up arms. This rolling action prevents a uniform feeding of the hemp into the pick-up means so that the stream of hemp flowing into the machine is of an uneven or non-uniform thickness. Yet another difficulty is found in the fact that long hemp is easily blown about by wind when it is raised from the ground, which wind acts to entangle and bunch the hemp as it travels through the machine. As a result of these difficulties considerable trouble has been encountered in accomplishing a complete and uniform turning over of the hemp.

It is an object of this invention, therefore, to provide an improved machine for turning over windrowed hemp or the like.

Another object of this invention is to provide a hemp turning machine in which windrowed

hemp is uniformly picked up and carried in a substantially smooth and unbroken stream into and through the hemp turning machine.

5 A still further object of this invention is to provide a machine for turning over windrowed hemp in which the hemp is uniformly picked up and carried in an unbroken stream into the machine on a pick-up structure having a width which is appreciably less than the over-all length of the hemp.

10 Another object of this invention is to provide a structure for continuously guiding the hemp or like material along its entire path of travel into and through a hemp turning machine in a smooth unbroken stream and without bunching or tangling.

15 A particular feature of this invention is found in the provision of a machine for turning over windrowed hemp, having a pick-up unit comprised of a series of downwardly and forwardly extended arms, in which a yieldably supported elongated guide unit is extended forwardly and upwardly from the arms and rearwardly of the arms to the hemp receiving platform of the machine. On advance of the machine along the ground the forward end portion of the guide unit passes over the butt ends of the hemp in a windrow to yieldably press the hemp toward the ground and prevent the hemp from rolling up ahead of the arms, while the remaining portions 20 of the guide unit support the hemp against the arms as the hemp is carried upwardly of the arms into the hemp turning machine, and against the hemp carrying table or platform on which the hemp is moved through the machine.

25 30 35 Other objects, features and advantages of this invention will become apparent from the following description when taken in connection with the accompanying drawings in which:

40 Fig. 1 is a plan view of a hemp turning machine embodying the hemp guide means of this invention, with parts of the hemp turning machine being broken away for the purpose of clarity;

45 Fig. 2 is an elevational side view of the hemp turning machine looking upwardly, as viewed in Fig. 1, and showing the relative assembly of the pick-up structure and guide means in the hemp turning machine, with a portion of the hemp turning machine being removed to more clearly show its construction;

50 Fig. 3 is an enlarged elevational side view of the machine looking down as viewed in Fig. 1 and showing the structure for delivering the hemp from the machine to the ground;

55 Fig. 4 is an enlarged sectional elevational view taken along the line 4—4 in Fig. 1 showing the drive means for the pick-up structure;

60 Fig. 5 is an elevational sectional view taken on the line 5—5 in Fig. 4 showing the hemp ex-

tended beyond the confines of the pick-up structure; and

Fig. 6 is a detail sectional view of the pick-up drive means as seen on the line 6—6 in Fig. 4.

Referring to the drawings the hemp turning machine of this invention is shown in Figs. 1, 2 and 3 as having a horizontal frame 10 including longitudinal frame members 11 and 11a. The frame 10 is supported on ground wheels 12 and 13 offset from each other longitudinally of the frame 10. Supported on the rear portions of the longitudinal frame members 11 and 11a is a horizontal platform 14 of substantially semi-circular shape having its flat side 16 facing toward the front of the machine. A vertical shaft 17 mounted on the frame 10 rotatably supports a rotary hemp feeder 18 movable over the platform 14 in a path concentric with the annular contour of the platform 14.

The hemp feeder 18 is comprised of an inner rim 19 and an outer rim 21 concentrically arranged in a horizontal plane and connected together by diametrically extended cross arms 22. Angularly spaced about each rim 19 and 21 and depending downwardly therefrom in a straddling relation to substantially the top level of the platform 14 are a plurality of inverted U-shaped spring fingers or prongs 23. Rotation of the hemp feeder 18 is accomplished by means including a pulley 24 which is assembled on the cross arms 22 in a superposed relation with the inner rim 19 and mounted on the shaft 17. Pulley 24 is connected by a belt 25 with a horizontal driving pulley 26 mounted on a vertical shaft 27 which is carried on the frame 10 on the forward ends of the longitudinal frame members 11 and 11a. The shaft 27 is operatively connected, through a gear box 28, with a drive shaft 29 to which power is supplied from a tractor or the like (not shown) for pulling the hemp turning machine over the ground.

In the operation of the machine, as it is advanced along a hemp windrow, the hemp to be turned over is picked up from the ground and carried to the receiving end 31 of the flat side 16 of the platform 14 by the combined action of the pick-up structure 32 and guide means 30 of this invention, which will be later described. As the hemp approaches the receiving end 31 it is engaged by the fingers 23 on the rims 19 and 21 of the hemp feeder 18 and moved horizontally on the platform 14 in a circular path to the delivery end 33 of the platform which is located substantially opposite the receiving end 31.

Ahead of the delivery end 33 are forwardly and downwardly curved rod portions 34 and 35 to be later explained (Figs. 1 and 3). On passage of the hemp between the platform delivery end 33 and the curved rod portions 34 and 35 the hemp is discharged to the ground, as is clearly shown in Fig. 3, and then turned over due to the travel of the machine over the ground. The discharged hemp is thus arranged in a windrow, laterally spaced from the first windrow from which it was picked up, but in a reverse or upside-down position relative to its position when in such first row.

As previously explained it is desirable that the hemp be supplied to the hemp turning machine in a substantially unbroken stream and uniformly turned over. This is accomplished in the present invention by the provision of the pick-up structure 32 and guide means, indicated generally at 30 and including the curved rod portions 34 and 35.

The pick-up structure 32 has a series of arms 38, 75

three of which are shown in Figs. 1 and 5. The arms 38 are pivotally mounted at one end on a shaft 39, located adjacent the receiving end 31 of the platform 14, and extend downwardly and forwardly away from the platform end 31 (Figs. 2 and 4). The arms 38 are held in a spaced relation axially of the shaft 39 by rods 40, each of which is pivoted at one end 40 on the shaft 39, and connected at an opposite end 40a to the forward portion of an associated pick-up arm 38 (Figs. 1 and 5). The lower or forward end of each arm 38 carries a sprocket 41 which is in alignment longitudinally of an arm with a corresponding sprocket 42 rotatably supported on the shaft 39. An endless conveyor 43 is arranged about each pair of sprockets 41 and 42 for travel along the top and bottom of an arm, with pick-up fingers 44 being carried in a spaced relation on a conveyor. The lower end of an arm 38 has a supporting sled or runner 46 on its under side to provide clearance for the fingers 44 relative to the ground.

The conveyors 43 are operated together from the shaft 39 through a driven gear 47, mounted on the shaft 39 and connected by a chain 48 with an idler gear 49 supported on a spring-tensioned bracket 51 pivoted at 52 on the frame 10 at a position rearwardly of the ground wheel 13 (Figs. 4, 5 and 6). Intermediate the gears 47 and 49, and in driving engagement with one side of the chain 48 is a driving gear 53 rotatably mounted on a shaft 54 for the ground wheel 13. Connection and disconnection of the driving gear 53 with the wheel shaft 54 to control the operation of the conveyors 43 is accomplished by a slip clutch mechanism 56, of a usual type, supported on the shaft 54 and actuated by a manually operated lever 57 connected with the clutch mechanism 56 through a lever system 58. It is seen, therefore, that the conveyors 43 are driven from the ground wheel 13 and that the hemp feeder 18 is driven from the tractor which pulls the hemp turning machine.

The guide means 30 includes a guide or press unit 37 which is comprised of an angulate rod having one end 59 pivoted in a bracket 61 carried on the frame member 11 (Figs. 1, 4 and 5). From its end 59 the rod 37 extends laterally outwardly and downwardly from the frame member 11, and then bends rearwardly in a straight rear portion 62 which extends upwardly in a spaced relation above the pick-up structure 32, substantially between the two inner pick-up arms 38, and terminates at the upper end of the pick-up arms. The forward portion of the guide rod 37 thus projects upwardly and transversely ahead of the pick-up structure 32, while its rear portion 62 extends upwardly and rearwardly in a spaced relation above the pick-up structure. It is seen, therefore, that the rod 37 is pivotally supported only at its forward portion on the frame member 11. The rod 37 is thus free to be pivoted or swung in an up and down direction about the pivot 59, with this pivotal action in turn varying the distance between the rod 37, and the ground and conveyors 43 for the purpose of maintaining a downward pressure on the hemp ahead of and travelling upwardly on the arms 38.

Connected at one end with the forward portion of the rod 37 at the transverse section thereof is a supporting rod 63, which is pivoted at its opposite end 64 on the frame member 11 at a position rearwardly of the pivot bracket 61 for the rod 37.

Thus referring to Fig. 4, the forward portion of the guide rod 37 rides across the top of the

windrowed hemp and presses downwardly on the hemp ahead of the pick-up arms to prevent the hemp from being rolled or bunched forwardly of the arms 38 by the action of the pick-up fingers 44. If the windrow becomes thick the rod 37 will be pivoted in an upward direction. This pivoting of the rod concurrently increases its clearance relative to the ground and to the conveyors 43. Should the windrow of hemp thin out the rod 37 will pivot downwardly to concurrently decrease its clearance relative to the ground and to the conveyors 43. The rod 37 is thus automatically operated in direct response to the thickness of the hemp windrow to continuously maintain a downward pressure both on the hemp ahead of the pick-up structure, and on the hemp carried on the pick-up structure 32. The rod 37 thus functions to maintain a uniform feeding of the hemp into the pick-up structure, and a uniform travel of the hemp on the pick-up 32.

A uniform travel of the hemp about the circular platform without bunching or tangling is accomplished by means including a guide rod 66 integrally formed with the rod portions 34 previously mentioned in connection with Fig. 3.

The rod 66, as shown in Fig. 1, is of a semi-circular shape corresponding to the platform 14 and in turn to the hemp feeder 18. The forward end portion of the rod 66 is extended longitudinally of the pick-up arms 38 and is pivoted at 67 to a transverse frame member 60 carried on the frame members 11 and 11a forwardly of the pick-up arms 38. The opposite end portion of the rod 66 terminates in the rod portions 34, three of which portions are illustrated in Fig. 1. The rod portions 34 are connected at a common point 67 to the rod 66 and diverge outwardly and are turned downwardly from the rod 66 as shown in Figs. 1 and 3. The center one of the three rod portions 34 has its free end pivoted at 68 in a bracket 69 supported on a transverse frame member 71 extended laterally outwardly from the frame member 11a. Cooperating with the rod portions 34, in guiding the hemp from the discharge end 33 of the platform 14 to the ground, is a rod 72 supported at one end on the transverse member 71 and curved upwardly and rearwardly from the member 71 in substantial alignment with the rod portions 34 in a direction transversely of the machine (Figs. 1 and 3).

The intermediate or semi-circular portion of the guide rod 66 is positioned on the platform 14 concentrically about the inner wheel 19 of the hemp feeder 18, the rod 66 normally resting directly on the platform 14. As the hemp carried on the pick-up structure 32 approaches the receiving end 31 of the platform 14 it engages and lifts the forward end portion of the guide rod 66, prior to passing out from under the rear portion 62 of the guide 31. Since the weight of the rod 66 is carried on the hemp, the downward pressure initially applied on the hemp by the rod 37 is continued by the rod 66 and maintained throughout the travel of the hemp on the platform 14. Since the rod 66 is pivotally supported at its opposite ends it is freely movable relative to the platform 14 and self-adjustable to always ride on the top of the hemp flowing through the machine.

The hemp holding, or pressing action of the guide rod 66, relative to the hemp on the platform 14, is supplemented by a ring 74 floatingly supported on bolts 76 from the inner rim 19 and depended therefrom between the legs of the spring pick-up fingers 23 on the rim 19 (Figs. 1

and 5). A coil spring 77 is mounted about each bolt 76 between the ring 74 and the bottom of the rim 19 to provide a yieldable downward pressure on the hemp as it tends to push the ring 74 upwardly.

In the operation of the hemp turning machine the forward end portion of the guide or press rod 31 travels over the butt ends of the hemp. During the advance of the hemp turning machine the forward portion of the rod 37 rides over the top of a windrow and packs or presses the hemp toward the ground at the time it is engaged by the pick-up fingers 44. By virtue of this pressing action by the forward portion of the guide rod 31 the hemp is prevented from rolling ahead of the pick-up structure 32 and bunching forwardly of the lower ends of the arms 38. Further, because of the packing of the hemp by the guide rod 37 at the lower ends of the pick-up arms 38 the hemp is uniformly gathered by the pick-up fingers 44 for carrying upwardly in a smooth stream on the conveyors 43.

As best shown in Fig. 5 an appreciable length of the hemp extends outwardly from the hemp turning machine. However, because of the rear portion 62 of the guide rod 37, and the forward end portion of the guide rod 66 being in a spaced and continuing relation over the pick-up structure 32 the butt or heavier ends of the hemp are supported against tipping upwardly away from the arms 38 and confined between the guide rods 37 and 66, and the pick-up structure. The positive feeding of the hemp into the pick-up structure 32 and the support of the hemp on the pick-up structure by the guide rod 37 thus combine to produce a smooth and unbroken flow of the hemp from the ground to the receiving end 31 of the platform 14. As the hemp approaches the upper ends of the arms 38 it is engaged by the fingers 23 of the hemp feeder 18 and the rod 66, the fingers 23 moving the hemp about the platform 14 for discharge at the delivery end 33 of the platform in the manner previously explained.

The rod 66 supports the butt ends of the hemp against the platform 14 and prevents any tipping of the hemp as it passes from the pick-up structure on to the platform. As clearly appears from Figs. 3 and 5 the hemp is confined between the rod 66 and the platform 14 over its full length of travel on the platform. All of the hemp thus moved is carried to the delivery end 31 of the platform and then guided to the ground by the curved rod portions 34 and the rod 72 which act to effectively remove all hemp from the fingers 23 so that no hemp is carried by the fingers 23 forwardly of the platform delivery end 33. Any variations in the thickness of the stream of hemp moving on the platform is accommodated by the up and down movement of the rod 66 relative to the platform 14. Further because of the continuous support of the hemp by the rod 37 against the pick-up structure 32 and by the rod 66 against the platform 14, the machine can be effectively operated on windy days without the wind acting to dislodge the hemp from a relative parallel aligned position and into an entangled condition.

Tangling of the hemp with the sprockets 42 at the upper ends of the arms 38 is eliminated by the provision of stripping or guard discs 79, corresponding in number to the pick-up arms 38 and mounted on the shaft 39 adjacent a sprocket 42 (Figs. 4, 5 and 6). Each disc 79 is of a diameter such that its periphery is at substantially

the ends of the fingers 44 when the fingers are passing around a sprocket 42. These guards function to strip the hemp from the fingers 44 about the time the hemp is initially engaged by the spring fingers 23 of the hemp feeder 18 so that the hemp passes smoothly from the conveyors 43 to the platform 14.

From a consideration of the above description it is seen that the invention provides a hemp turning machine in which windrowed hemp is positively picked up from the ground and conveyed into the hemp turning machine in a smooth unbroken stream and without the hemp becoming tangled or bunched in any way. The guide or pressure means for accomplishing this desideratum is simple and compact in design and provides for the practical use of a pick-up structure having an over-all width which is appreciably less than the over-all length of the hemp being gathered. Although hemp has been referred to specifically in the description it is to be understood that the pick-up structure and guide means of this invention is also applicable to any like material adapted to be cut in windrows.

It is to be understood also that only a preferred embodiment of the invention has been illustrated and described and that changes and modifications can be made therein which are within the full intended scope of this invention as defined by the appended claims.

I claim:

1. In a machine for turning over windrowed hemp with the butt ends of the hemp at one side of a windrow, pick-up means including a series of downwardly and forwardly supported arms spaced transversely of said machine, endless conveyors corresponding to said arms, with a conveyor extending along the top and bottom of an associated arm, pick-up fingers carried on each conveyor, an elongated guide member, means pivotally supporting said guide member for up and down pivotal movement, with said guide member having a straight portion extended rearwardly in a spaced relation above said arms and another portion curved upwardly and forwardly of said arms, said guide member, on advance of said machine along the ground, being at said one side of a windrow, with said curved portion adapted to ride across said butt ends to urge the hemp against the ground ahead of said arms, and said straight portion being yieldably engageable with the said butt ends to support the hemp on said pick-up means against longitudinal tipping movement.

2. In a machine for turning over windrowed material, a horizontal platform of semi-circular shape having a material receiving portion adjacent one end of its flat side and a material discharge portion adjacent the opposite end of its flat side, with said flat side constituting the forward end of said platform, means for moving the material from said receiving portion to said delivery portion, a pick-up structure extended forwardly and downwardly from said receiving portion, means for pressing the windrowed material ahead of said pick-up structure against the ground, and for supporting the gathered material on said pick-up structure, having one end portion curved and a substantially straight opposite end portion, means pivotally supporting said pressing means at said curved end portion for up and down pivotal movement, with said curved end portion being positioned ahead of said pick-up structure, and said straight portion

located in a spaced relation above said pick-up structure, means for supporting the gathered material against said platform comprising a member having an arcuate form corresponding to the circular contour of said platform, means movably supporting said member for up and down movement relative to said platform, said member having one end projected over said pick-up structure adjacent the straight portion of said pressing means, and an opposite end at said material delivery portion constituting a deflector for directing the material at said delivery portion toward the ground.

3. In a machine for turning over windrowed material, a horizontal platform of semi-circular shape having a material receiving portion at one end of its flat side and a material delivery portion at the opposite end of its flat side, means for moving the material in a circular path from said receiving portion to said delivery portion, a pick-up structure extended forwardly and downwardly from said receiving portion, means for supporting the gathered windrowed material against said pick-up structure and platform including a member extended from a point forwardly of said pick-up structure and upwardly in a spaced relation over said pick-up structure, and an arcuate member spaced above said platform and positioned between said receiving portion and delivery portion, with said arcuate member having a deflector at said delivery portion for directing the material from said platform toward the ground.

4. In a machine for turning over windrowed material, a downwardly and forwardly extended pick-up means, an elongated guide member having an upwardly and forwardly curved front end portion located forwardly of said pick-up means and a portion of a substantially straight form extended upwardly and rearwardly in a spaced relation above said pick-up means, means pivotally supporting said pick-up means for up and down pivotal movement, said curved portion, on advance of the machine along a windrow, being moved in riding engagement across the windrowed material to yieldably urge said material against the ground, and said straight portion being adapted to ride on said material to support the material against said pick-up means as the material travels upwardly on said pick-up means.

5. In a machine for turning over windrowed material, a horizontal platform having a material receiving portion and a material delivery portion, means for moving the material from said receiving portion to said delivery portion, means for picking up and carrying the windrowed material to said receiving portion, means for yieldably urging the material ahead of said pick-up means against the ground, and for yieldably urging the picked up material against said pick-up means comprising an elongated member rideable on said material and having a front portion located forwardly of said pick-up means, and a rear portion extended upwardly and rearwardly above said pick-up means, means pivotally supporting said elongated member for up and down pivotal movement, means for yieldably urging the material against said platform between said receiving portion and said delivery portion, and means movably supporting said last mentioned means for up and down movement relative to said platform.
